US00D597398S

(12) **United States Design Patent**
Jones et al.

(10) **Patent No.:** US D597,398 S
(45) **Date of Patent:** ** Aug. 4, 2009

(54) **WINDOW LOCK HANDLE AND COVER**

D304,292 S 10/1989 Bobrowski

(75) Inventors: **Sherry L. Jones**, Pataskala, OH (US);
Brian Dallmann, Owatonna, MN (US)

(Continued)

(73) Assignee: **Truth Hardware Corporation**,
Owatonna, MN (US)

Primary Examiner—Prabhakar Deshmukh

(**) Term: **14 Years**

(74) *Attorney, Agent, or Firm*—Patterson, Thuente, Skaar &
Christensen PA

(21) Appl. No.: **29/323,044**

(57) **CLAIM**

(22) Filed: **Aug. 15, 2008**

The ornamental design for a window lock handle and cover,
as shown and described.

(51) **LOC (9) Cl.** **08-07**

(52) **U.S. Cl.** **D8/337; D8/331**

(58) **Field of Classification Search** D8/330,
D8/331, 301, 302, 306, 309, 400, 337, 338;

FIG. 1 is a perspective view of a window lock handle and cover showing our new design, shown in its environmental use;

FIG. 2 is a top plan view of the window lock handle and cover depicted in FIG. 1;

FIG. 3 is a bottom plan view of the window lock handle and cover depicted in FIG. 1;

FIG. 4 is a rear elevation view of the window lock handle and cover depicted in FIG. 1;

FIG. 5 is a front elevation view of the window lock handle and cover depicted in FIG. 1;

FIG. 6 is a side elevation view of the window lock handle and cover depicted in FIG. 1; and,

FIG. 7 is an opposing side elevation view of the window lock handle and cover depicted in FIG. 1.

The broken lines are included for the purpose of illustration and form no part of the claimed design. The broken lines immediately adjacent to the shaded areas represent the boundaries of the claimed design. None of the broken lines form part of the claimed design.
